UNITED STATES PATENT OFFICE.

CHARLES HOWARD SMITH, OF SHORT HILLS, NEW JERSEY, ASSIGNOR TO INTERNATIONAL COAL PRODUCTS CORPORATION, OF RICHMOND, VIRGINIA, A CORPORATION OF VIRGINIA.

CARBONIZING FURNACE RETORT.

1,409,597.

Specification of Letters Patent. Patented Mar. 14, 1922.

Application filed April 3, 1918. Serial No. 226,410.

To all whom it may concern:

Be it known that I, CHARLES HOWARD SMITH, a citizen of the United States, and a resident of Short Hills, in the county of 5 Essex and State of New Jersey, have invented certain new and useful Improvements in Carbonizing Furnace Retorts, of which the following is a specification.

The invention relates to a furnace having 10 a retort or retorts for carbonizing briquets therein, and an object of the invention is to construct a furnace wherein a large number of briquets can be readily and economically carbonized so as to commercially produce 15 the desired resulting briquets.

The invention is particularly directed to a furnace for the carbonizing of briquets, made as from raw coal or from a partially carbonized residue and which coal or partially carbonized coal residue has admixed therewith binding material, such as pitch, and which binding material ensures or renders possible firm, coherent briquet structures, when raw briquets made from 25 said mixture are carbonized at sufficiently high temperatures and for a sufficient length of time.

In my Patent Number 1,276,429, granted August 20, 1918, entitled Briquets and 30 method of making the same, I have described a manner in which strong, coherent, free-burning, smokeless briquets can be produced by partially carbonizing a high volatile coal, by adding to the partially carbonized coal a proper mixture of binding material, such as pitch, by forming the resulting mixture into briquets, and by subsequently carbonizing the raw briquets thus formed.

40 In my Patent No. 1,334,180 granted March 16, 1920, entitled Method of manufacturing briquets, I have described a manner in which coals of a non-caking type can be formed into strong, coherent, free-burning, smokeless briquets by first mixing with the 45 non-caking coal, when in finely divided form, a proper admixture containing caking coal and a binding material, such as pitch, by forming the resulting mixture into the 50 raw briquets and by carbonizing the raw briquets thus formed at a sufficiently high temperature and for a sufficient length of time.

The present invention is particularly di-

rected to the commercial performing of the 55 carbonizing operation employed in carrying out the inventions described in the patents above referred to. The carbonizing of the raw briquets is carried out in what may be referred to as an oven but what is in fact 60 an enclosed carbonizing retort, or retorts, from which the vaporous and gaseous products that are given off during the carbonization are conducted to any suitable storage means and made available for future use. 65

The carbonizing furnace may therefore be properly referred to as a furnace retort but it is more frequently referred to as an inclined carbonizing furnace since the floors of the ovens or retorts that provide the carbonizing compartments or carbonizing spaces slope downwardly from the charging end of the furnace toward the discharging end thereof. The carbonizing compartments or carbonizing spaces are preferably arranged in sets. The carbonizing compartments or spaces in each set are vertically arranged and the construction which defines the carbonizing compartments or spaces is such that the member or part which provides 70 the floor of one carbonizing compartment or space becomes or provides the roof of the carbonizing compartment or space immediately below it. On each side of the tier of vertically arranged carbonizing compartments there is located a vertically arranged tier of combustion chambers or flues which have suitably controlled means whereby the heat conditions can be readily controlled 75 within each combustion chamber or flue and by this construction each carbonizing oven and each particular portion thereof is under control. The furnace is also preferably provided with a recuperator, which is a means 80 for heating the incoming air, that is employed or required to support combustion that takes place in the combustion chamber of the furnace from the hot gases leaving the furnace. The recuperator is preferably 85 of masonry, to wit, brick, constructed so as 90 to provide alternately arranged series of air ducts or conduits and waste gas ducts or conduits. With such a construction there is 95 a ready interchange or transference of heat from the hot gases to the cold incoming air 100 through the masonry walls that define the ducts, passageways or conduits of the recuperator.

The invention relates to the features above referred to as well as to other features which are hereinafter clearly described and fully set forth in the appended claims.

5 As illustrating a specific embodiment of the inclined carbonizing furnace or furnace retort wherein the invention can be and is realized reference is made to the accompanying drawings forming a part of this 10 specification in which drawings,

Figure 1 is a vertical view of the charging end of the inclined carbonizing furnace.

Figure 2 is a vertical transverse sectional view taken adjacent to the charging end of 15 the inclined carbonizing furnace. This figure is a view of the furnace taken on the plane indicated by the line 2—2 of Figures 5, 6, 7, 8 or 9 looking in the direction of the arrows.

20 Figure 3 is a vertical view of the charging end of the inclined carbonizing furnace.

Figure 4 is a vertical transverse sectional view taken adjacent to the discharging end 25 of the inclined carbonizing furnace. This figure is a view of the furnace taken as on the plane indicated by the line 4—4 of Figures 5, 6, 7, 8 or 9 looking in the direction of the arrows.

Figure 5 is a vertical longitudinal sectional view through the carbonizing retort 30 of the furnace and also through a portion of the recuperator and particularly that portion of the recuperator which defines the air ducts, conduits or passageways through 35 which the air that is employed to support the combustion travels prior to being delivered where combustion takes place. This Figure 5 is a view taken as on the plane indicated by the line 5—5 of Figures 1, 2, 3 4, 40 8 or 9.

Figure 6 is a vertical longitudinal sectional view showing the arrangement of the 45 heating flues of the combustion chambers which are arranged along the walls which define the sides of the carbonizing chambers; in other words, along the side walls of the carbonizing chambers. In this view there are also shown the ducts, conduits or passageways through which the products of 50 combustion, to wit, the spent gases, pass after leaving the combustion flues or chambers and when on their way to the atmosphere. It is from the waste gases passing through the conduits that the heat is derived 55 for preheating the air which is employed to support the combustion as heretofore indicated. This Figure 6 is a view of the furnace taken as on the plane indicated by the broken line 6—6^m—6ⁿ—6 of Figures 1, 2, 3 60 or 4; or, as on the plane indicated by the line 6—6 of Figure 7 looking in the direction of the arrows.

Figure 7 is a view looking downwardly 65 upon a section of the furnace. In this figure that portion through each carbonizing cham-

ber is a view taken as on the plane indicated by the broken line 7—7^m—7 of Figure 5 looking in the direction of the arrows, while that portion through each combustion flue or chamber is a view taken as on the plane indicated by the broken line 7—7^m—7ⁿ—7' of Figure 6 looking in the direction of the arrows.

Figure 8 is a horizontal sectional view taken as on the plane indicated by the line 75 8—8 of Figure 5 or Figure 6 looking in the direction of the arrows.

Figure 9 is a horizontal sectional view taken as on the plane indicated by the line 9—9 of Figures 4, 5 or 6 looking in the direction of the arrows.

Figure 10 is a vertical sectional view taken as on the plane indicated by the line 10—10 of Figure 5 or Figure 6 looking in the direction of the arrows. In other words, Figure 10 is a vertical sectional view showing in the upper portion thereof the arrangement of the carbonizing chambers and the combustion chambers or flues arranged alongside of the carbonizing chambers to 90 which they correspond and all together constitute the carbonizing portions of the furnace, while below in the lower portion of the figure there are shown alternate air and waste gas ducts which are located in what 95 constitutes the recuperator. In Figure 7 and also in Figure 10 the parts are shown on a somewhat larger scale than in the other figures.

Figure 11 is a diagrammatic cross-section 100 through the apparatus, illustrating the method and means employed for charging and discharging the retorts.

The inclined carbonizing furnace has four vertically extending walls, to wit, the transversely and vertically extending wall 1 at the charging end of the furnace, the transversely and vertically extending wall 2 at the discharging end of the furnace, the longitudinally and vertically extending main 110 wall 3 at the right hand side of the furnace, and the longitudinally and vertically extending main wall 4 at the left hand side of the furnace. The inclined furnace also has a roof 5 that extends from end wall to 115 end wall and from side wall to side wall. This roof slopes downwardly from the charging end of the furnace to the discharging end thereof; in other words, a longitudinal section of the furnace will show the roof 120 is declined from the charging end of the furnace. A transverse section of the furnace will show that the roof extends horizontally from one main side wall to the other. The carbonizing portion of the furnace is designated by 6 and the recuperator is designated by 7. The carbonizing portion 6 and the recuperator 7 are separated by the main floor member or main intermediate member 8 which slopes downwardly from the charging 130

end of the furnace toward the discharging end thereof and serves to define the lower floor member of the carbonizing chamber or chambers and also the roof of the recuperator. This main floor member 8 in longitudinal cross-section slopes downwardly from the charging end of the furnace to the discharging end thereof, but a transverse sectional view of the furnace shows that this floor 8 extends horizontally from one main side wall of the furnace to the companion main side wall.

Referring now to the carbonizing portion of the furnace, it will be observed that there are three sets of carbonizing chambers or retorts each designated by 6^x and each carbonizing chamber or retort is subdivided by means of shelves or partitions, as 6^a, into carbonizing compartments or carbonizing spaces 6^b. The briquets to be carbonized can be inserted into the several carbonizing chambers by opening the doors 9, or by charging through the gas outlet header 10 when a cover or door 11 upon the latter has been removed. In other words, each inclined carbonizing chamber or retort is charged by opening the upper end and the chamber or retort is closed when the charging is completed; it, therefore, remains closed while a carbonizing operation is in progress.

It will be understood that when a carbonizing operation is being performed these chambers or retorts are air tight; or, in other words, are sealed whereby no air can enter the interior of the retorts. The discharge end of each carbonizing chamber or retort during the carbonizing operation is closed or sealed by doors, 12, which can be opened to permit a discharge or emptying of the carbonizing chamber of the contents—to wit, the carbonized briquets as they are termed—when a carbonizing operation has been completed. The opening of the doors 12 whereby the carbonized briquets are discharged and the carbonizing chamber is emptied may be referred to as the opening of the lower end of the retort. A header 10 is provided for each carbonizing chamber or retort 6^x and the vaporous and gaseous products evolved during the carbonization pass from the retort 6^x through header 10, pipe 13, cross-fitting 14, hand-controlled valve 15 and pipe 16 into hydraulic main 17 which is common in apparatus for making and obtaining coal gas products. The side walls of each set of carbonizing chambers or retorts 6^x are defined by the vertically and longitudinally extending walls 6^c which may be referred to as the vertically and longitudinally extending intermediate walls since they are located intermediate the main side walls 3 and 4. These intermediate walls serve as means whereby heat is transferred by conduction from the heating flues hereinafter referred to to the interior of the carbonizing

chamber. Each of these vertically and longitudinally extending intermediate walls extends the full length of the furnace from the end wall at the charging end of the furnace to the end wall at the discharging end. Each 70 of these intermediate walls also extends the full distance from the main floor member or main intermediate member 8 to the roof 5.

It will hereinafter be seen that the main floor member or main intermediate member 75 8 is suitably supported by the recuperator construction which will be hereinafter described more in detail. The vertically and longitudinally extending intermediate walls 6^c serve to give vertical support to the central longitudinal portion of the main roof 5 to which they extend. These vertically and longitudinally extending intermediate walls 6^c receive proper lateral support as will hereinafter appear (see particularly 80 Figure 10) whereby they will be properly maintained in place as the furnace is used, and whereby they can also perform the function of supporting the main roof 5, as above pointed out. A series of combustion flues 85 or heating flues—the combustion flues in each series constituting collectively a combustion chamber—is arranged along the side of each carbonizing chamber 6^x. Each of these series of combustion flues or heating flues—90 95 the combustion chamber—is designated by 18^x or 18^y (see particularly Figure 10). That series located between the vertically and longitudinally extending main wall of the furnace and the carbonizing chamber or 100 retort nearest to said wall is designated by 18^x, while the series located between adjacent carbonizing retorts, or in other words, between adjacent longitudinally and vertically extending intermediate walls of adjacent 105 retorts is designated by 18^y. The series 18^x is similar to 18^y with the exception that the series 18^x is somewhat smaller than the series 18^y because of the necessity of the latter being common to two sets of chambers 110 or retorts. Each heating flue of the series 18^x is designated by 18^{ax} and each heating flue of the series 18^y is designated by 18^{ay}. The flues 18^x are separated by partitions 18^{bx} while the flues 18^{ay} are separated by partitions 18^{by}. These flues or partitions are sometimes referred to as heating flue partitions or as combustion flue partitions.

Fuel, preferably gas, is supplied to the interior of the heating flues through valve-controlled pipes 19 and this fuel is mixed with heated air which is delivered from the passageways 18^{ex} and 18^{ey}—leading from the recuperator 7—through openings 18^{dx} and 18^{dy}. The openings 18^{dx} are controlled as by 12 sliding dampers 18^{ex} and the openings 18^{dy} are controlled as by sliding dampers 18^{ey}. The dampers can be positioned by the operator to control the supply of air to the interior of each combustion or heating flue 18^x or 18^y.

18^{ay} as the case may be. It will therefore be seen that as the gas supply is a valve-controlled supply and as the air supply is under the control of the operator the amount 5 of heat within the combustion flue is readily controllable at the intake end thereof. Each combustion flue however is controlled at its discharge end whereby the flow of the burned or burning gases from the combustion 10 chamber can be regulated. This control is by means of the dampers 18^{tx} and 18^{ty} which control the passageways, as 18^{ex} and 18^{ey}, that open into passageways or conduits 18^{hx} and 18^{hy} leading to the recuperator. It will therefore be seen that the flow 15 of the burning or spent gases from each heating flue is under the control of the operator. In this way the control of the heat within each combustion chamber and 20 the consequent control of all of the heat supply to each portion of the carbonizing chambers or retorts is attainable.

An inspection of Figure 10 when taken in conjunction with Figure 6 will make it clear 25 that the partitions 18^{bx} serve not only to separate the combustion flues 18^x but also serve to convey lateral support to the vertically and longitudinally extending wall 6^c from a vertically and longitudinally extending main side wall as 3 or 4, as the case may be. The partitions 18^{by} extend parallel to the partitions 18^{bx}; they also extend from the charging end of the furnace to the discharging end thereof, as do the partitions 18^{bx}. 30 Bearing this in mind and from an inspection of Figure 10 it will be readily observed that the partitions 18^{by} serve to connect and laterally support adjacent vertically and longitudinally extending walls 6^c of adjacent carbonizing chambers or retorts 6^x.

It will also be remembered that the shelves or partitions 6^a that are within the carbonizing chambers or retorts 6^x serve to connect and in this way render lateral support 45 to the vertically and longitudinally extending walls 6^c of the retort in which they are located, and an inspection of Figure 10, as has been heretofore pointed out, will make it clear that each vertically and longitudinally extending wall 6^c is, by means of these partitions such as 18^{bx}, 6^a and 18^{by}, suitably laterally braced. A further inspection of 50 Figure 10, however, will make it clear that the joints, so to speak, are broken. In other words, from this figure it will be seen 55 that the shelves or partitions 6^a are not in alinement with a set of partitions, as 18^{bx} and 18^{by}.

In the heating of briquets in the carbonizing chambers it is desirable to have full effective heat, as in corners 6^d, and therefore the heating flues are arranged so as to be opposite the point of juncture of the shelves or partitions 6^a and the vertically and longitudinally extending intermediate walls 6^c.

In other words, each shelf or partition is opposite combustion flues adjacent thereto. The several partitions, to wit, the partitions 18^{bx} and 18^{by} between the combustion flues or chambers and also the shelves or partitions 6^a between the carbonizing compartments or spaces 6^b and substantially parallel with each other. These partitions slope downwardly and rearwardly. The partitions 18^{bx} and 18^{by} between the combustion flues extend the 75 entire length from the wall at the charging end of the furnace to the wall at the discharging end thereof, but the shelves or partitions 6^a between the carbonizing compartments or spaces 6^b terminate somewhat 80 short of the charging end of the furnace in order to allow a common receiving space within the chamber or retort at the charging end of the furnace. Because of the shelves 6^a dividing each carbonizing chamber into carbonizing compartments arranged one above the other and because of the common receiving space just referred to, it will be manifest that the carbonizing compartments or spaces 6^b may be referred to as 85 communicating carbonizing compartments arranged one above the other and due to this arrangement a single gas outlet header as 10 can be relied upon for the passage of vapors and gases given off from the several 90 carbonizing compartments 6^b in each carbonizing chamber as the furnace retort is functioning.

Referring now to the recuperator portion of the furnace and tracing first the path of 100 the hot-spent gases leaving the heating flues, it will be remembered that the gases first pass through the damper controlled openings 18^{ex} and 18^{ey} into and downwardly through the passageways or conduits 18^{hx} and 18^{hy}. From the passageway 18^{hx}—or 18^{hy}—as the case may be, the gases take a sinuous path through the conduits or passageways 20^a to 20^m inclusive that are provided in the masonry of the recuperator. 110 The spent gases after being cooled or partially cooled leave the recuperator through passageway 20^m. The passageways 20^a, 20^b, etc., are defined by overlapping shelves or partitions, such as 20^u to 20^v inclusive, part of 115 which shelves or partitions extend from the vertically and transversely extending wall at the charging end of the furnace toward either the underside of the inclined sloping main floor member 8, or toward the wall at the discharging end of the furnace, terminating however short of the sloping main floor or said last mentioned wall. The rest of the partitions extend from the inclined sloping main floor construction or from the wall at the discharging end of the furnace toward the wall at the charging end thereof but terminate short of the latter. The vertically extending side walls that provide the 120 sides of the passageways through which the 125

spent gases travel also provide the sides of the passageways through which the incoming air passes. The vertically extending walls just referred to are designated by 21. 5 These walls 21 extend vertically and longitudinally of the furnace for the full length thereof, from end wall to end wall, and they may be referred to as longitudinally and vertically extending walls of the recuperator. 10 These walls 21 also extend from the foundation upon which the furnace retort as a whole is placed up to the underside of the inclined main floor member or main intermediate member 8. These walls, therefore, 15 serve to properly support the central longitudinal portions of the inclined main floor member 8. Incoming air enters the openings 22 and flows in a sinuous path through the passageways designated by 22^a to 22^k inclusive and finally enters the horizontally and transversely extending passageway or header opening 23, as it may be called. 20 From this header opening 23 the heated air can pass through openings 24 controlled by dampers 24^a into the passageways or conduits 18^{ex} or 18^{ey} from whence they pass from damper controlled openings 18^{dx} or 18^{dy}, as the case may be, into the combustion flues, as 18^x and 18^y. 25 An inspection of the drawings will make it clear that the incoming cold air is first opposite the cooler vertically extending walls along which the cooled or partially spent gases are traveling and that the air 30 as it is gradually heated moves along to the hotter zones where the hottest spent gases can be availed of to still further heat the air to the maximum temperature. 35 The masonry construction which provides the air ducts, conduits or passageways, as 40 they may be called, resembles in many respects the masonry construction which provides the waste gas conduits or passageways, as will be manifest from a comparison of Figures 5 and 6. Figure 5, however, which 45 shows the air ducts, clearly illustrates a construction which is employed to enable the passing of the heated air to the end of the furnace where the initial combustion takes 50 place. This therefore requires conduits, such as 22ⁱ, 22^j and 22^k that extend from one end of the furnace to the other end and which are made possible by the employment of a zigzag partition 25 which as a whole is parallel with the inclined sloping main floor 55 8 but which is spaced from the latter. The passageways 22^a, 22^b, etc., are defined by the partitions 22^m to 22^t inclusive. A part of these partitions extend from the vertically and transversely extending wall at the 60 charging end of the furnace toward the zigzag partition 25, or the vertically and transversely extending wall at the discharging end of the furnace, and they terminate short 65 of either the zigzag partition or the wall at the discharging end of the furnace. The rest of the partitions extend from the zigzag partition 25 toward the wall at the charging end of the furnace but terminate short of the latter. Passageways through which the 70 air being heated and also through which the waste gases pass are unobstructed so as to permit a ready flow of air or gases through the respective air ducts or gas ducts, as the case may be. The partitions 20ⁿ, 20°, 20^p, 75 etc. and the partitions 22^m, 22ⁿ, etc. extend horizontally and transversely, and they extend from one vertically extending intermediate wall 21 of the recuperator to the adjacent vertically extending wall 21, or to the 80 vertically extending main walls 3 or 4, as the case may be, and an inspection of Figures 2 and 10 will make it clear that the vertically extending intermediate walls 21 of the recuperator are well braced against lateral 85 disruption. 80 The furnace above described is particularly adapted for the carbonizing of raw briquets that contain volatile binding material, such as pitch. One form of briquets 90 which I have treated in this furnace is made in the following manner: 95 I have taken a partially carbonized coal which was formed by distilling a raw coal having a thirty-six per cent (36%) volatile content and a specific gravity of 1.3 at temperatures of between 800 degrees F. to 1200 degrees F. until there was produced a uniform carbonized residue—the partially distilled coal—having a volatile content of 100 approximately ten per cent (10%) and which residue had an apparent specific gravity of eight-tenths (0.8). This residue or partially carbonized coal I have crushed and intimately mixed with it approximately ten 105 per cent (10%) of coal tar pitch and fluxed and formed the resulting mixture into raw briquets by pressure. Each of these raw briquets had for example approximately fifteen and one-half per cent (15½%) volatile. 110 It will here be remarked that when the raw briquets contained partially carbonized coal and had been made according to the process outlined in my Patent No. 1,276,429 such raw briquets contained approximately between eleven per cent (11%) to seventeen per cent (17%) hydrocarbon volatile matter; the percentage of volatile matter was relied upon to ensure or enable the development of the requisite binding qualities which had 115 been developed during the carbonization carried out in the furnace described herein. The raw briquets were then introduced into the carbonizing chambers or retorts 6^x until each retort was practically full. In the 120 retort the briquets were subjected to a distilling operation at temperatures up to 1850 degrees F. until there remained in the briquets only about one and one-half per cent (1½%) to two and one-half per cent (2½%) 125 130

volatile matter. These briquets the carbonized briquets were then removed from the oven and thoroughly cooled, as by quenching. The resulting briquets after air drying had, in rough figures, about two and one-half per cent (2½%) volatile matter and a carbon content of approximately ninety per cent (90%) and an apparent specific gravity of 1.53.

- 10 The resulting briquets each had a strong, coherent structure, retained its shape during combustion, that is did not break apart or crumble while being burned but was gradually consumed, was non-metallic in appearance and was relatively free burning and had many of the characteristics of anthracite coal. The resulting carbonized briquets were of the same shape as but smaller in volume than the briquets originally charged.

15 In the carbonizing of briquets having a binding material such as pitch there will be a disrupting or rupturing of the briquets during the carbonizing operation, if the 20 briquets are piled too high upon each other. In the carbonizing of briquets having pitch as a binding material there is a period wherein the pitch is in a more or less plastic or molasses-like condition and when in this 25 condition it does not have sufficient tensile strength to hold the solid coal particles of the briquet together, if the briquets are heavily loaded.

- 30 In the present type of furnace the heating of the briquets is carried out under such conditions that the pitch will remain soft for only a short period of time at the most. The heat is sufficiently high to effect an early conversion from this soft or plastic 35 condition into a condition where the solid coal particles are cemented or bound together. In order to avoid the encountering of the objections just referred to, and which are liable to take place unless the heating is 40 properly carried out, and also in order to effect a quick conversion of the binding material into a condition where it will cement or hold the solid coal particles of the briquet together, each carbonizing chamber or 45 retort 6^x is subdivided or provided with the several carbonizing compartments or spaces 6^c.

50 An important problem in the development of this furnace has been to obtain a relatively high capacity and this has been realized by the employment of the superposed carbonizing compartments or spaces which permits a relatively deep pile, so to speak, of briquets in any one carbonizing chamber, 55 but the shelves or partitions 6^a break up the load so that only a relatively small pressure can be exerted against any one briquet. In this way there is little likelihood of the briquets becoming mutilated or ruptured.

55 The slope of the several floors—which are

provided by the main floor member 8 and the several shelves or partitions 6^a—is such that there is a slight tendency for the briquets to slide from the charging end of the furnace to the discharging end thereof and, 70 consequently, upon the doors at the discharging end of the furnace being opened the contents of the retort can be readily discharged. This slope is also availed of in the charging of the furnace since it is necessary that the raw briquets fed through the charging openings will readily find their proper location in the carbonizing compartments or spaces for the carbonizing operation.

75 At the temperatures herein mentioned, to wit, 1850 degrees F. substantially all of the volatile content remaining in the partially carbonized coal and that in the pitch binding material—with the exception of the two and one-half per cent (2½%) volatile matter or whatever percentage of the volatile matter be left in the resulting briquet—is eliminated from the raw briquets by the carbonizing operation and this volatile can be 80 recovered from the hydraulic main—either in gaseous or liquid form—to which it is conducted by the piping heretofore described. The temperatures at which the carbonizing operation is performed may be 85 varied, in fact may run as low as 1400 degrees F. or may run as high as 2250 degrees F. or thereabouts, and the length of time for the carbonizing operation will of course 90 depend upon the character and size of the 100 raw briquets charged to the furnace, upon the heat to which they are subjected when in the carbonizing retorts and upon the volatile content in the final carbonized briquet. The temperature, however, should be enough 105 to develop the cementing qualities which are attained by the use of the pitch binding material or whatever other binding material may be employed for this purpose.

95 It is preferred to charge the furnace and 110 discharge same by means of the apparatus illustrated diagrammatically in Figure 11. Mounted upon the platform 26 is a charging device comprising a car 27 running along rails 28 parallel with the charging 115 end of the furnace. This car is divided into compartments 28^a, 28^b, 28^c and 28^d which contain enough raw briquets to properly fill each carbonizing compartment, and there is provided for each compartment 28^a, 28^b, 28^c and 28^d a movable or telescoping chute 29 which bridges the space between the car 27 and the carbonizing compartments and serves to conduct the raw briquets as from the compartment 28^b of the car 27 to the second highest compartment of the furnace. When the carbonizing operation is proceeding, the doors 9 (see Figures 1 and 5) and 12 (see Figures 3 and 5) at both ends of the carbonizing compartments are, of course, 120 125 130

closed, and after the treatment has been effected to the desired extent the door 12 is opened to permit the charge contained within the retort in question to pass into the 5 dump-car 30 mounted on rails 31 parallel to the discharging end of the retort.

It will be noted that the briquets are supported upon inclined surfaces during the carbonizing operation, and that the doors 10 at the bottoms of the carbonizing compartments serve to retain the charges of briquets during the carbonizing period.

While I have described particularly the manufacture of carbonized briquets made 15 from partially carbonized coal, still it will be understood that the furnace is adaptable for use in the manufacture of briquets from raw coal as a base material or even from coke where a binding material, such as pitch 20 or other hydrocarbon binder, is employed.

The furnace shown in the drawings is illustrated as a single furnace. It will be manifest, however, that this furnace may become one of a battery of furnaces and it 25 will also be noted that each main side wall of the furnace might become and be considered as a side wall common to two furnaces. It might even be considered as a main side wall for either furnace on each 30 side thereof, or it might be considered in effect an intermediate wall.

The improvements herein set forth are not limited to the precise construction and arrangement shown and described for they 35 may be embodied in various forms and modifications without departing from the spirit and scope of the invention.

What I claim is:

1. A briquet carbonizing furnace of the 40 class described having vertically and transversely extending walls at the charging and discharging ends thereof, vertically and longitudinally extending main side walls, a main roof and a main floor member each 45 extending longitudinally from the wall at the charging end to the wall at the discharging end and from one main side wall to the other main side wall, intermediate walls arranged in sets and extending vertically from the main floor member to the main roof member, and also longitudinally from one end wall to the other, providing 50 between the intermediate walls of each set a carbonizing chamber, spaced transverse partitions extending from the intermediate wall of one set to the adjacent intermediate wall of the adjacent set whereby the space between the adjacent sets is subdivided into combustion flues, spaced transverse partitions 55 extending from the outermost intermediate wall to the main side wall adjacent thereto whereby the space between the outermost intermediate wall and its adjacent side wall is subdivided into combustion 60 flues, and means for supplying heat to said 65

combustion flues, said furnace being characterized by having one or more shelves in each carbonizing chamber extending from the intermediate wall at one side of the chamber to the intermediate wall at the 70 other side of the chamber which serves to divide the said chamber into carbonizing compartments or spaces, and upon which shelf or shelves briquets are supported while being carbonized.

2. A carbonizing furnace comprising in combination longitudinally and vertically extending main side walls, transversely and vertically extending end walls connecting said main side walls, a main roof and a 80 main floor member extending from one main side wall to the other, vertically and longitudinally extending intermediate walls each of which provides a side wall for a carbonizing chamber, said furnace being characterized by having transverse partitions in each carbonizing chamber extending from one wall of the chamber to the opposite wall, and dividing each chamber into a series of vertically arranged carbonizing 85 compartments and also by having transverse heating flue partitions, some of the transverse heating flue partitions being between each vertically extending main side wall on the one hand and the intermediate 90 wall adjacent thereto on the other, and other transverse heating flue partitions are between each side wall of each carbonizing chamber and the side wall of the adjacent carbonizing chamber.

3. In a briquet carbonizing furnace of the class described having vertically and transversely extending walls at the charging and discharging ends thereof, spaced vertically extending main side walls extending longitudinally from one end wall to the other, a main roof and a main floor member sloping downwardly toward the wall at the discharging end, intermediate walls arranged in sets and extending vertically from the main floor member to the main roof member and from one end wall to the other to provide between the intermediate walls of each set a carbonizing chamber, partitions between intermediate walls of adjacent sets and between each outer intermediate wall and the main side wall adjacent thereto whereby the space at the outside of each intermediate wall of each intermediate set is subdivided into combustion flues, and means for supplying heat to said combustion flues, said furnace being characterized by having one or more shelves in each carbonizing chamber sloping downwardly toward the discharging end of the furnace and dividing the carbonizing chamber into communicating carbonizing compartments arranged one above the other.

4. A carbonizing furnace of the class described comprising in combination vertically 130

- and longitudinally extending main side walls, a main roof and a main floor member sloping downwardly in a longitudinal direction from the charging end of the furnace 5 toward the discharging end and extending in a horizontal direction from one main side wall to the other, and vertically and longitudinally extending intermediate walls spaced from each other and arranged in sets 10 to provide carbonizing chambers between the walls of each set, said furnace being characterized by having one or more shelves in each chamber sloping downwardly toward the discharging end of the furnace and extending transversely and horizontally from one intermediate wall to the companion intermediate wall, and by having heating flues arranged one above the other and along the outside of each intermediate wall, the sides 15 of each of which flues are defined either by an inner portion of the main side wall and an outer portion of the intermediate wall adjacent the side wall, or by the outer portions of adjacent intermediate walls of adjacent sets, the roof of each of which flues is defined either by an under side portion of the main roof or by a partition between the flues, the bottom of each of which flues is defined either by an upper portion of the 20 main floor member or by a partition between the flues.
5. A furnace for carbonizing briquets comprising in combination longitudinally and vertically extending main side walls, a roof member and a main floor member extending from one side wall to the other, vertically and longitudinally extending intermediate walls each of which provides a side wall for a carbonizing chamber, partitions or shelves in each carbonizing chamber extending from one wall of the chamber to the opposite wall, and dividing each chamber into a series of vertically arranged carbonizing compartments, heating flue partitions between each vertically extending main side wall on the one hand and the intermediate wall adjacent thereto on the other, and a series of heating flue partitions extending from each side wall of each carbonizing chamber to the side wall of the adjacent carbonizing chamber, the construction being such that each partition or shelf is located opposite the flues adjacent thereto.
6. A furnace for carbonizing briquets comprising in combination longitudinally and vertically extending main side walls, transversely and vertically extending end walls, a main roof member and a main floor member extending horizontally from one side wall to the other and inclined downwardly from the end wall at the charging end of the furnace to the end wall at the other end of the furnace, and vertically and longitudinally extending intermediate walls each of which provides a side wall for a carbonizing chamber, said furnace being characterized by having partitions in each carbonizing chamber extending from one wall 70 of the chamber to the opposite wall and dividing each chamber into a series of vertically arranged carbonizing compartments by having a set of heating flue partitions between each vertically extending main side 75 wall on the one hand and the intermediate wall adjacent thereto on the other, and by having other sets of heating flue partitions, the partitions being so arranged that the partitions constituting each set extend from 80 an intermediate wall for each carbonizing chamber to the intermediate wall for the adjacent carbonizing chamber, the construction of the intermediate walls being such that heat is transferred by conduction from 85 the heating flue to the interior of the carbonizing chamber.
7. A furnace for carbonizing briquets comprising in combination longitudinally and vertically extending main side walls, 90 transversely and vertically extending end walls connecting said side walls, a roof and floor member extending from one side wall to the other and inclining downwardly from the end wall at the charging end of the furnace to the other end of the wall and vertically and longitudinally extending intermediate walls extending from end wall to end wall and from the floor member to the roof, each of which intermediate walls provides a side wall for a carbonizing chamber, said furnace being characterized by having sloping partitions in each carbonizing chamber extending from one wall of the chamber to the opposite wall and dividing 95 each chamber into a series of vertically arranged carbonizing compartments, by having heating flue partitions between each vertically extending main side wall on one hand and the adjacent intermediate wall on the 100 other, and by having sets of sloping heating flue partitions, the partitions of each set extending from an intermediate wall of each carbonizing chamber to an intermediate wall of the adjacent carbonizing chamber, each 105 of said intermediate walls constituting a side wall for a carbonizing chamber, transferring heat by conduction from said flues to the interior of said carbonizing chambers.
8. A briquet carbonizing furnace having 110 carbonizing compartments or spaces inclined from the charging end of the furnace toward the discharging end and arranged one over the other so that the roof for one compartment or space becomes the floor of or for 115 the compartment or space immediately above, the construction being such that the side walls which delineate the sides of said compartments or spaces merge into or become a continuation of each other, means 120

for supplying heat which is transferred by conduction through said side walls to the interior of said compartments, and means for collecting or withdrawing gases driven off 5 during a carbonizing of briquets within said compartments.

9. A carbonizing furnace having a vertically and transversely extending end wall at the charging and discharging ends thereof, 10 longitudinally and vertically extending main side walls, a roof member and a main floor member sloping downwardly toward the discharging end of the furnace, a recuperator in the lower portion of the furnace structure 15 and carbonizing chambers in the upper portion of the furnace structure separated by said main floor member, spaced intermediate walls extending from the base of the furnace structure vertically toward the main floor 20 member to provide a series of alternating air and waste gas ducts, partitions connecting said intermediate walls and spaced from each other and arranged to form sinuous air ducts, partitions connecting the walls, between which there are waste gas ducts and 25 arranged so as to define sinuous passageways for waste gases, pairs of longitudinally and vertically extending intermediate walls extending from the main floor member to the roof and from end wall to end wall to define the sides of said carbonizing chambers, transversely extending shelves for separating a carbonizing chamber into carbonizing compartments one above the other, combustion 30 flue partitions connecting the intermediate wall of one pair with the intermediate wall of an adjacent pair and connecting the intermediate wall of one pair with a side wall adjacent thereto to define 35 with the rest of the masonry structure a series of combustion flues arranged along each intermediate wall which defines in part a carbonizing chamber, passageways for conducting waste gases from the said combustion 40 flues to the entrance of said waste gas ducts, a header passageway into which the air ducts discharge, and conduits or passageways extending from said header passageway to the entrance end of the combustion 45 flues. 50
10. A carbonizing furnace having a vertically and transversely extending wall at each end thereof, longitudinally and vertically extending main side walls, a roof and a main floor member sloping downwardly toward the discharging end of the furnace, a recuperator in the lower portion of the furnace structure and carbonizing chambers in the upper portions of the furnace structure 55 separated by said main floor member, vertically arranged intermediate walls extending from the base portion of the furnace structure upwardly to the main floor member and providing alternating air ducts 60 and waste gas ducts, partitions connecting the walls and defining sinuous passageways for the air and waste gas, longitudinally and vertically extending intermediate walls arranged in pairs or sets and extending from the main floor member to the roof and from 70 end wall to end wall to define with the rest of the furnace structure said carbonizing chambers, transversely extending shelves sloping downwardly toward the discharging end of the furnace for separating a carbonizing chamber into vertically arranged carbonizing compartments, partitions connecting the intermediate wall of one set with the intermediate wall of an adjacent set and the intermediate wall of one set with 75 the adjacent main side wall to define with the rest of the masonry structure combustion flues or chambers arranged along the intermediate side walls which define in part the carbonizing chambers, passageways for 80 conducting the waste gases from said flues to the entrance end of said waste gas ducts, and valve controlled passageways or ducts leading from the delivery end of the air ducts to the entrance end of the combustion 85 flues or chambers. 90
11. A carbonizing furnace having a vertically and transversely extending end wall at the charging and discharging end thereof, longitudinally and vertically extending main 95 side walls, a roof and a main floor member sloping downwardly toward the discharge end of the furnace, a recuperator in the lower portion of the furnace structure, carbonizing chambers in the upper portion of the furnace 100 structures, which recuperator and carbonizing chambers are separated by said floor member, intermediate walls extending vertically from the base of the furnace and providing alternating air and waste gas ducts, 105 partitions defining sinuous passageways for the air passing inwardly through the recuperator and for the waste gas passing outwardly through the recuperator, longitudinally and vertically extending intermediate 110 walls arranged in pairs and extending from the main floor member to the roof and from one end wall to the other and defining with the rest of the furnace structure said carbonizing chambers, transversely extending 115 shelves for separating a carbonizing chamber into vertically arranged carbonizing compartments, partitions connecting the intermediate wall of one pair with the intermediate wall of an adjacent pair and each 120 main side wall with an intermediate wall adjacent thereto to define with the rest of the masonry structure combustion flues arranged along the intermediate side walls that in part define the said carbonizing chambers, 125 valve controlled passageways for conducting waste gases from said flues to the entrance of said waste gas ducts, a header passageway into which the air ducts discharge, valve controlled passageways extending from said 130

header passageway to the entrance of the combustion flues, and means for supplying fuel to the interior of said combustion flues.

12. In a briquet carbonizing furnace of the kind described, a plurality of superposed inclined carbonizing shelves, side walls for and common to said shelves, means for retaining a charge of briquets within the compartments defined by said walls and inclined shelves, and means for heating said com-

partments by heat which is transferred by conduction through said side walls to the interior of the compartments.

This specification signed and witnessed this 2nd day of April A. D., 1918.

CHARLES HOWARD SMITH.
